UNITED STATES PATENT OFFICE.

PETER BEST, OF ELIZABETH, NEW JERSEY.

TROLLEY-BASE.

SPECIFICATION forming part of Letters Patent No. 793,344, dated June 27, 1905.

Application filed September 29, 1904. Serial No. 226,491.

To all whom it may concern:

Be it known that I, PETER BEST, of Elizabeth, in the county of Union and State of New Jersey, have invented a new and Improved Trolley-Base, of which the following is a full, clear, and exact description.

My invention relates to improvements in trolley bases or supports which are attached to the tops of trolley-cars to support the pole and trolley.

The object of my invention is to produce a very simple and compact device which can be used in connection with ordinary trolley poles and cars, which enables the pole to be let down practically flat with the car and turned around when necessary, which is constructed in such a way as to turn very easily, which has a convenient means for regulating the spring tension on the pole, which is also constructed in such a way that when the pole is lowered the tension thereon will be reduced to almost nothing, and which in general provides an efficient durable watertight trolley-support in which the parts are practically arranged and easily accessible.

To these ends my invention consists of certain features of construction and combinations of parts, which will be hereinafter described and claimed.

Reference is to be had to the accompanying drawings, forming a part of this specification, in which similar figures of reference indicate corresponding parts in all the views.

Figure 1 is a side elevation of my improved device. Fig. 2 is a rear elevation of the same. Fig. 3 is a detail section of the turret or cap forming a part of the invention, and Fig. 4 is a sectional plan on the line 4-4 of Fig. 2.

The device is provided with a base portion 10, preferably in the form of a cylinder, and in any event having a cylindrical interior, this base portion or cup being also provided with flanges 11 to the end that it may be easily attached to a car-top. Projecting centrally upward from the bottom of the base portion or cup 10 is a standard or post 12, which is reduced and screw-threaded at its upper end, as shown at 13, so that the said portion may receive nuts 14, which are adapt-

ed to fasten in place the cap or turret 15, and the latter fits snugly on the top of the nut 10 and overlaps the side edges of the latter, so as to make the said cup water-tight. The cap or turret 15 has a central hollow depending guide 16, which is adapted to fit on over the post 12, and the bottom wall of the cap or turret 15 is preferably inclined upward and outward from the center, as shown at 17, to provide a suitable bearing-surface for the 55 rollers presently referred to. The cap or turret has also a bore 20 extending upward from the hollow guide 16 to receive the reduced end 13 of the post 12, and the superstructure or bracket 18 of the turret is recessed, as shown at 19, to provide for getting 60 at the nuts 14. The bracket part 18 of the turret is reduced as a matter of convenience; but it will be of course understood that this is a mere matter of design and that the exterior shape of any of the parts is not very 65 essential.

Within the cup or base portion 10 is a spider having a ring 21, which encircles the guide 16, and arms 22, on which are loosely 75 mounted the rollers 23, which fit the top and bottom walls of the chamber in the cup 10, the bottom wall being the bottom of the cup and the top wall being the part 17 of the turret or cap 15. The spider just referred to is 80 an important feature of the invention, and it will be seen that it serves perfectly to keep the rollers 23 properly spaced, so that they shall bear evenly on the parts intended to run on them, and they are prevented from 85 crowding or grinding together—an objection common to bearing-rollers.

The turret has in the bracket portion 18 a horizontal way 24, in which is held the slide-block 25, and this is recessed longitudinally, 90 as shown at 26, to provide for the adjusting-screw 27, which extends longitudinally in the slide-block, the threaded portion fitting an upwardly-extending boss 28 on the bracket 18 and the screw being journaled in the depending part 25^a of the block 25, while the outer end of the screw is preferably squared, as shown at 29, so that a wrench can be conveniently applied to it. It will be seen that by turning the screw in or out the slide-block 95 100

25 can be similarly moved, and in this way the tension of the springs 31 can be nicely adjusted. These springs are arranged on opposite sides of the bracket 18 and are attached 5 to studs 30 on opposite sides of the slide-block 25, and the opposite ends of the springs are attached to the upturned lower end of the base 32 of the trolley-pole 33, which base is pivoted, as shown at 34, on the upwardly-extending boss 35 at the top of the bracket 18. Obviously any suitable connection can be 10 made between the part 32 and the ordinary trolley-pole, or the part 32 might be the pole itself. The object of having the boss 35 and the upturned part 32^a of the trolley-pole is to 15 enable the spring 31 to almost center when the pole is tipped flat, as shown by dotted lines in Fig. 1, and so the tension on the pole 32 is greatly reduced and the pole can be very 20 easily manipulated when brought down to the position stated. It will be seen that this construction also makes a very compact arrangement, and to further facilitate this the part 32 is preferably bifurcated, so that it can 25 shut down over the part 35. It will also be noticed that the whole device is extremely compact and water-tight, that the turret portion turns very easily on the roller-bearings, and that for this reason the turret can be

easily turned around completely, so that the trolley-pole will extend to either end of the car as desired.

Having thus fully described my invention, I claim as new and desire to secure by Letters Patent—

1. A trolley-base, comprising a hollow base or cup portion having means for attachment to a car, a turret mounted on the hollow base and constructed to carry a trolley-pole, a vertical guide arranged between the hollow base and the turret, a spider independent of both base and turret, and comprising a ring turning freely on the guide, and radial arms, and bearing-rollers on the arms of the spider the said rollers fitting against the hollow base and the bottom of the turret.

2. In a trolley-base, the combination with the turret and the pole pivoted thereon, of the slide-block movable in and out of the turret, the said block being hollowed out to form a housing, a nut portion on the turret, and a screw journaled in the slide-block and contained in the hollow thereof, the said screw engaging the nut portion on the turret.
